SHANK PIECE AND METHOD OF MAKING
THE SAMERenfrew D. Laird, Brockton, Mass., assignor, by
mesne assignments, to United Shoe Machinery
Corporation, Paterson, N. J., a corporation of
New Jersey

Application February 5, 1937, Serial No. 124,280

4 Claims. (Cl. 12—146)

This invention relates to improvements in shank pieces and to improved methods of making shank pieces. The invention is herein illustrated in its application to the manufacture of fabricated or composite shank pieces of the type comprising a filler piece of relatively soft material, such as fiberboard or leatherboard, and a metallic stiffener strip which is secured by means of tacks to the filler piece.

10 In making shank pieces of the type referred to the tacks are passed through tack holes previously punched in the metallic strip and after the points of the tacks have been driven through the filler piece they are bent over and clenched against the lower surface of the latter. The tacking of the stiffener strip to the filler piece may be accomplished by hand or by machinery and in order that the points of the tacks shall be entered within the tack holes in the stiffener strip and the 20 tacks properly positioned for the tack driving operation it has been customary to make the tack holes substantially larger than the shanks of the tacks. Consequently, after the tacks have been driven there is considerable space between the 25 shanks of the tacks and the edges of the tack holes. When a shoe having such a shank piece is being worn the movements of the foot tend to bend or flex the shank piece and thus to cause the stiffener strip and the filler piece to creep back and forth relatively to each other in directions lengthwise of the shoe so as repeatedly to take up and restore the play between the shanks of the tacks and the edges of the tack holes. Moreover, continued wear of the shoe has some 35 tendency to loosen the tacks so as eventually to provide play between the stiffener strip and the heads of the tacks. These conditions are undesirable inasmuch as objectionable metallic or clicking noises are liable to be made when portions of the stiffener strip strike against the tacks. It is even possible, as a result of the necessary handling of the shank pieces incident to packing and shipping, for the parts of some of the shank pieces to become loosened so that they will chatter or rattle, a condition tending to make it appear that the manufacture of the shank pieces 45 has not been accomplished with the proper care and workmanship.

One object of the present invention is to insure against such undesirable conditions as those above referred to and to insure that the component parts of the composite shank pieces shall remain tightly secured together so long as the shank pieces are in use.

50 With this object in view it is proposed to strike

up a plurality of spurs adjacent to the edges of the tack holes in the stiffener strip at its outer or lower side, i. e., the side which is to face the filler piece, and to embed these spurs in the substance of the filler piece in the operation of tacking the stiffener strip thereto and thus positively to prevent any relative creeping of the parts. As herein illustrated, the tack-receiving holes in the stiffener strip are made by punches shaped and operated to form the spurs so that, as the tacks 10 are being driven, the shanks of the tacks will be tightly and firmly gripped by the spurs and thus securely held against any tendency to become loosened relatively to the stiffener strip. Thus, even though the tacks may subsequently become 15 somewhat loosened in the filler piece, there will be no play between the tacks and any portions of the metallic stiffener strip and consequently no possibility that any objectionable metallic noises will be produced after the shank piece has been 20 incorporated in a shoe. As also illustrated, the tack holes are formed with flaring or bell-mouthed openings at the upper side of the stiffener strip and the heads of the tacks are countersunk in these openings as a result of the tack- 25 driving operation so that the upper surfaces of the tack heads are substantially flush with the upper surface of the stiffener strip and thus have no tendency to produce undesirable protuberances. In practice, and as herein illustrated, the 30 points of the tacks are bent over and clenched against the lower surface of the filler piece so that the bent-over points will tend to prevent any substantial loosening of the tacks in the filler piece and will serve to maintain the spurs of the 35 stiffener strip embedded in the filler piece to counteract any influences tending to cause the parts of the shank piece to creep relatively to one another.

The invention will now be described with reference to the accompanying drawing, in which

Fig. 1 is a perspective view of the stiffener strip showing the upper side thereof;

Fig. 2 is a view in longitudinal section and on an enlarged scale illustrating the operation of forming a tack hole in the stiffener strip;

Fig. 3 is a sectional view, on an enlarged scale, taken on the line III—III of Fig. 1;

Fig. 4 is a fragmentary perspective view on a 50 still further enlarged scale of a portion of the stiffener strip positioned with its lower side uppermost to show the spurs that are struck up adjacent to one of the tack holes;

Figs. 5 and 6 are perspective views similar to 55

Fig. 4 but showing modified constructions and arrangements of the spurs;

Fig. 7 is a view, partially in cross-section and partially in elevation, illustrating the operation of tacking a stiffener strip to a filler piece;

Fig. 8 is a sectional view, on an enlarged scale, taken along the line VIII—VIII of Fig. 7;

Fig. 9 is a perspective view of the completed shank piece showing the upper side thereof;

10 Fig. 10 is a sectional view, on an enlarged scale, taken along the line X—X of Fig. 9; and

Fig. 11 is a perspective view of the shank piece showing the lower side thereof.

As shown in the drawing, the improved shank

piece comprises a filler piece 14 and a stiffener strip 16 which is secured to the filler piece by means of tacks 18 the heads 20 of which engage the upper side of the stiffener strip and the pointed ends 22 of which are clenched against the lower surface of the filler piece. The filler piece 14 may advantageously be made of such material as leatherboard or fiberboard and, as shown, is shaped in outline to fit within and substantially fill the space between the edges of the overlasted margins of a shoe upper. The stiffener strip 16 may consist of a narrow strip of hardened steel having the usual or any desired amount of longitudinal curvature.

The stiffener strip 16 is provided with tack holes 24 which are preferably located in or near the opposite end portions of the strip. The tack holes are preferably made in the stiffener strip before the steel is hardened and in such a manner as to form flaring or bell-mouthed openings 26 (Fig. 3) at the upper side of the strip and to strike up more or less sharply pointed spurs or prongs 28 at the lower side of the strip adjacent to the edges of the hole. The tack holes may conveniently be formed by means of punches 30 such, for example, as the punch 30 (Fig. 1) having more or less tapered or rounded end portions, the punches operating in conjunction with a work support (such as the anvil 32) having suitable openings registering with the punches. The tack holes 24 are made large enough to receive the tacks readily and the flaring upper portions at least of the holes are made substantially larger than the shanks of the tacks to facilitate the entrance of the tacks into the holes and to enable the heads of the tacks to be practically countersunk within the tack holes by the blows of the tack drivers so that the upper surfaces of the heads will be nearly or substantially flush with the upper surface of the stiffener strip and thus will have no tendency to form undesirable humps or ridges. The punching of the tack holes may result in the striking up of two, three or more spurs adjacent to the edges of the holes at the outer or lower side of the strip and the extent of the penetrating or puncturing strokes of the punches is regulated so that the lower, more or less sharp and pointed ends of the spurs will be disposed so as to engage and tightly to grip the shanks of the tacks as the latter are being driven through the holes. It has been found practicable and desirable to regulate the punching operation so as to form only two oppositely disposed spurs, such as those shown at 28 in Figs. 3 and 4, or so as to form three spurs shaped and arranged substantially as indicated at 28 in Fig. 6. In instances where only two spurs are formed they may be disposed relatively to the strip as indicated in Fig. 4 or as in Fig. 5. After the punching operation has been completed the stiffener strips are preferably subjected to the

usual hardening operation which hardens the strips, including the spurs, to such an extent that the driving of the tacks will not appreciably alter the shape of the spurs or spread them apart.

In attaching a stiffener strip to a filler piece 5 these parts may conveniently be assembled upon a work support, such as an anvil 36 (Fig. 7), having recesses 38 so arranged as to register with the shanks of the tacks and so shaped as to 10 clench the points of the tacks against the filler piece. The tacks, after having been positioned with their pointed ends within or in line with the tack holes in the stiffener strip, are driven through the holes and through the filler piece by means of devices such as the illustrated driver 15 40. The tacks are preferably made of soft ductile material as in accordance with the usual practice and tacks are selected of a size such that as they are being driven they will have to be forced or wedged through the restricted openings between 20 the lower ends of the spurs so as to insure that the spurs will grip or clutch the shanks of the tacks and thus function positively to hold the tacks against any subsequent heightwise movement relatively to the stiffener strip after the 25 tacks have once been driven into place. In practice it has been found that the sharp end or edge portions of the hardened spurs actually bite or plow into the relatively soft metal of the tacks so that they may actually form furrows in the 30 shank portions of the tacks, the furrows extending lengthwise of the shank portions as indicated at 42 in Figs. 7 and 8, and thus hold the tacks most effectively against both heightwise and turning movements. The force of the blows 35 delivered by the tack drivers is sufficient to embed the individual spurs quite deeply into the substance of the filler piece and thus to insure against any relative creeping of the stiffener strip and the filler piece. Moreover, the tack-driving 40 operation results in causing the ends of the tacks to be clenched against the lower surface of the filler piece and the heads of the tacks to become practically countersunk within the flaring openings of the tack holes, as best indicated in Fig. 7. 45

ings of the tack holes, as best illustrated. It will be seen that the gripping of the tacks by the spurs positively prevents loosening of the tacks so as to insure that there will be no play between the tacks and the stiffener strip and consequently no objectionable clicking or metallic noises such as that above referred to. Moreover, the shank piece itself, inasmuch as its component parts are maintained firmly and tightly secured together, is a more workmanlike article of manufacture and one which is better adapted for its intended purpose. 55 50

Having described my invention, what I claim as new and desire to secure by Letters Patent of the United States is:

1. A fabricated shank stiffener unit comprising a non-metallic filler piece, a hardened steel stiffener strip disposed in face-to-face engagement with said filler piece and having a plurality of tack-receiving holes therein, a group of pointed spurs struck up from said strip and projecting from its outer or lower side around each of said holes and embedded within the material of said filler piece, and headed tacks of soft ductile material, one in each of said holes, the shanks of said tacks extending through said filler piece and having furrows extending lengthwise thereof and said spurs firmly gripping the shanks of said tacks within said furrows to hold the tacks against both heightwise and turning movements. 60 65 70

2. A fabricated shank stiffener unit comprising 75

ing a non-metallic filler piece, a hardened steel stiffener strip disposed in face-to-face engagement with said filler piece and having a plurality of bell-mouthed tack-receiving holes therein, a group of pointed spurs struck up from said strip and projecting from its lower side around each of said holes and embedded within the material of said filler piece, and headed tacks, one arranged in each of said holes with its head seated within the bell-mouthed portion of the hole, said tacks having furrowed shank portions extending through said filler piece and clenched over against the outer side thereof and said spurs extending into the furrows in the shank portions of said tacks to hold the tacks from turning.

3. That improvement in methods of making fabricated shank stiffener units which consists in puncturing a steel stiffener strip at a plurality of points thereby forming a plurality of tack-receiving holes in the strip and in the puncturing operation striking up a group of pointed spurs adjacent to each of said holes, hardening said strip, assembling the hardened strip and a relatively soft filler piece in face-to-face relation with the spurred side of the strip facing the filler piece, and driving headed tacks of soft ductile material through said holes and through said

filler piece and in said tack-driving operation individually embedding said spurs within the material of the filler piece and wedging the soft shanks of the tacks between the hardened points of said spurs so that they will be tightly gripped by the spurs.

4. That improvement in methods of making fabricated shank stiffener units which consists in punching a plurality of bell-mouthed tack-receiving holes in an unhardened steel stiffener strip and in the course of said operation striking up a group of downwardly converging spurs adjacent to each of said holes, hardening said strip, assembling said strip and a filler piece of fibrous sheet material in face-to-face relation with the spurred side of the strip facing the filler piece, and driving headed tacks of soft metal through said holes and through said filler piece and in the course of said operation embedding said spurs in the filler piece, seating the heads of the tacks within the bell-mouthed portions of said holes, wedging the soft shanks of the tacks tightly between the hardened points of said spurs thereby causing the spurs tightly to grip the tacks, and clenching the points of the tacks against the outer side of the filler piece.
